(57) **CLAIM**

The ornamental design for a clothes hanger, as shown and described.

DESCRIPTION

FIG. 1 is a perspective view of a clothes hanger in accordance with the present design;

FIG. 2 is a top plan view of the clothes hanger of FIG. 1;

FIG. 3 is a left-side elevation view of the clothes hanger of FIG. 1, the right-side elevation view being a mirror image thereof;

FIG. 4 is a bottom plan view of the clothes hanger of FIG. 1;

FIG. 5 is a front elevation view of the clothes hanger of FIG. 1; and,

FIG. 6 is a rear elevation view of the clothes hanger of FIG. 1.

The broken lines shown in the drawing disclosure are for illustrative purposes only and form no part of the claimed design.
